KITCHEN UTENSIL HANDLE

Richard G. Furness, Colebrook, Conn.
(R.F.D. 2, Winsted, Conn.)

Filed Oct. 8, 1964, Ser. No. 82,102

Term of patent 14 years

(Cl. D44—29)

FIG. 1 is a top plan view of a kitchen utensil handle, showing my new design;

FIG. 2 is a side elevational view;

FIG. 3 is a bottom plan view;

FIG. 4 is an end elevational view taken from line 4—4 in FIG. 2; and

FIG. 5 is a sectional view taken on line 5—5 of FIG. 2.

I claim:

The ornamental design for a kitchen utensil handle, substantially as shown.
